INDUSTRIAL OVEN

Carl F. Mayer, Lakewood, Ohio

Application July 8, 1952, Serial No. 297,735

7 Claims. (Cl. 263—19)

1

This invention relates to industrial ovens, particularly of the class used in foundries and similar plants for drying freshly made cores and the "green" sand linings of ingot and other large and heavy mold flasks.

In ovens of the class referred to the work is supported upon portable racks or cars and, with the oven closed, heated gas (using the term in its broad sense to embrace air) is continually forced into the oven, and at least a major part of said gas is simultaneously withdrawn, reheated and recirculated, any remaining part being exhausted to the atmosphere and replaced by fresh air that is drawn into the system at one place or another, as about the doors, through the heater as combustion air, and possibly elsewhere, as will be readily understood.

Heretofore the supply ducts, from which the heated gas is discharged directly into the oven, have been located along the side walls near the floor, and the so-called recirculating ducts and exhaust ducts have been situated within the oven adjacent the top thereof. This arrangement was doubtless dictated by the well known principle that warm air rises, and the obvious fact that such action is accelerated by the natural stack draft to which the exhaust ducts are subjected, sometimes augmented by the suction of an exhaust fan or blower.

While such a circulating system has generally been regarded as satisfactory, its efficiency and reliability have been greatly impaired in many instances by damage to the supply ducts resulting from the said ducts being struck and deformed by parts of the work that, because the work has been improperly placed upon the cars, project too far beyond the sides of the conveyances. Lack of care in arranging the work on the cars and rough handling of the equipment, both of which contribute to the difficulty, are more or less prevalent in foundries, where the work that is being handled is usually very heavy and cumbersome.

The two principal objects of my invention are to improve the circulation, and the distribution and diffusion, of the hot gas through the oven thereby to increase the efficiency of the latter; and to arrange the ducts so that none is within reach of any part of the work with which the portable racks or cars are loaded.

In the attainment of these objects I arrange the supply ducts, and the exhaust ducts, if any, at the top of the oven, and the recirculating ducts, each preferably in the form of a trench, below the floor level of the oven.

2

A further and important advantage resulting from such a duct arrangement is the availability of substantially the full width of the oven space for work accommodation. To this end, the width of the door opening is made to correspond substantially to the internal transverse dimension of the oven. Accordingly, it will be seen that my invention provides maximum capacity relative to the external width of the oven.

10 I have said that the recirculating duct or ducts of my improved oven are below the floor level, each desirably in the form of a trench. It is a further object of my invention to house in such trench or trenches the car pulling means, which 15 may take the conventional form of a pull-cable, or an endless chain.

While my invention is not particularly limited to ovens of the so-called car type, nor to ovens that are open at both ends, I have chosen to so 20 illustrate it herein; and although a lift door is preferable for closing an open end of the oven as herein shown, other kinds of doors may be employed.

The above enumerated objects and advantages, 25 with others that will appear as this description proceeds, are attained in the embodiment of the invention illustrated in the accompanying drawings wherein like parts are designated by like reference numerals throughout the several views.

30 In the drawings,

Fig. 1 is a front elevational view of an industrial oven constructed in accordance with the invention;

Fig. 2 is a plan view of the oven; 35 Fig. 3 is a sectional side elevation of the oven, the plane of section being indicated by the line 3—3 of each of Figs. 1, 2 and 4, the view being shortened to avoid further reduction of the scale to which it is drawn by breaking away the ends 40 and insetting them beneath the major portion of the view;

Fig. 4 is a transverse section through the oven on the line 4—4 of each of Figs. 2 and 3, this view being drawn to a somewhat larger scale 45 than the others.

The oven comprises a casing, designated generally by the reference numeral 1, including a top wall 2 and side walls 3, the latter being shown as mounted upon curbs 5 that are integral with 50 and rise from a floor 6 of suitable material, such as concrete. The walls 2 and 3 are illustrated in a conventional manner as being of insulating material, and in practice they may be composed of panels of appropriate size that consist of 55 sheet metal shells filled with suitable insulation

and held together by a structural iron framework, all of which is well known to those familiar with this class of ovens, and, furthermore, has nothing to do with the invention at hand.

The casing 1 is shown as open at each end, entirely from one side wall to the other, and from the floor upwardly to a shallow drop wall or lintel 8. Thus, in the present form of the invention, the oven is provided with an entrance at one end and an exit at the other. Guides 10, which may be in the form of outwardly opening angles, rise from the floor on opposite sides of each end of the oven casing immediately adjacent thereto, and arranged with its lateral edges within the opposed guides 10 at each end of the oven casing is 15 a door that is slightly greater in height than the opening with which it is associated. The door that is located at what may be regarded, for the present purpose, as the entrance to the oven is designated 12, and the one located at the exit is 20 designated 13. The door 12 is insulated and may be of the same general construction as the wall panels above described. A beam 14 extends between and is suitably connected to the upper ends of the guides 10 of each pair, and mounted thereon are pillow blocks or bearings 15 wherein is journaled a shaft 16. It will be observed that the pillow blocks or bearings are arranged in pairs, and between those of each pair is a sprocket 17 that is suitably secured against rotation to the shaft 16. A chain 18 is engaged over each of the sprockets 17 and has one of its ends connected at 19 to the top of the door 12 or 13 and its other end anchored at 20 to the beam 14. Riding within a depending loop of each chain, between the anchored end thereof and the corresponding sprocket 17, is a rotary guide or sprocket 21 that has suitable connection with a counterweight 22. Said weight is shown as a bar that is common to all of the chains located at the corresponding end of the oven. One end of the shaft 16 has driving connection, through suitable reduction gearing enclosed in a casing 25, with an electric motor 27, said casing and motor being supported on a shelf 28 that extends laterally from the adjacent guide 10. Through the customary circuits and remote control switch (not shown), the motor 27 may be operated in reverse directions to raise and lower the corresponding door.

Located within the oven casing adjacent the top wall 2 are supply ducts 30 and 31, shown as of the same cross sectional size and shape, and a somewhat narrower supply duct 32. The ducts 30 and 31 are preferably fitted within the top corners of the casing and extend from one end of the oven to near the opposite end thereof. The duct 32 is of the same length as the ducts 30 and 31, and is desirably located substantially midway between the two. The duct 32 has outlet openings 33 in its side walls, and similar openings 34 in its bottom wall, while the ducts 30 and 31 have outlet openings 35 in their inner vertical walls and relatively wide outlet openings 36 in their bottom walls. In accordance with common practice, the outlet openings of the supply ducts are equipped with damper plates so that the quantity of gas discharged by said ducts may be regulated. As will best appear from Fig. 2, the supply ducts communicate with one another through cross ducts 38. Communicatively connected to the supply duct 31, through an upwardly divergent conduit 40, is the outlet of an impeller or blower 41, said conduit 40 entering the oven casing through an opening in the adjacent side wall 3. The impeller or blower 41 is shown as supported upon 75

the floor alongside the oven casing, incidentally in axial alignment with a heater 42 of conventional type commonly used in connection with recirculating systems of industrial ovens. The heater may be of the oil or gas fired variety to which ambient air is admitted for combustion purposes. The outlet of the heater communicates with the inlet of the impeller or blower 41 through a conduit 44. In order to conserve heat, the conduits 40 and 44 and the casings of the impeller or blower 41 and heater 42 may be encased in insulating material, as indicated. An electric motor 45 is shown as having driving connection, through a belt 46, with the shaft 47 of the impeller or blower 41.

An exhaust duct 50, provided with inlet openings 51, is supported within and transversely of the oven casing in the horizontal plane of the previously described supply ducts and adjacent the entrance end of the oven. Obviously, the supply ducts may be made shorter, so that another exhaust duct may be located at the exit end of the casing, if desired. An exhaust fan or blower 53 is shown as mounted on top of the oven casing, and the inlet thereof is placed in communication with the exhaust duct through a conduit 54 that extends through an opening in the top wall of the oven casing. The outlet of the fan or blower 53 opens into an exhaust stack 55. An electric motor 56 has driving connection, through a belt 57, with the shaft 58 of the fan or blower 53.

Situated below the level of the floor 6, which desirably consists of a solid monolithic structure, and opening through the floor into the interior of the oven casing, are relatively narrow elongated depressions or formations providing trenches 60 that constitute recirculating ducts. Although I have shown two such trenches, one of a somewhat larger capacity may be employed, in which case it would preferably be located at about the longitudinal center of the casing. This alternative arrangement is so obvious that specific illustration thereof is deemed unnecessary. The two trenches communicate with each other through a cross duct 62, and with the heater 42 through a subterranean conduit 63. The top of the cross duct 62 may be closed by extending the floor 6 thereover, or said cross duct may be open at the top, as are the trenches 60, if additional capacity of the gas recirculating facilities is desired.

The trenches 60 extend substantially the full length of the oven casing, and each is shown as disposed centrally of a track composed of parallel rails 65 that are set into the floor. The tracks 55 may lead from the area of the foundry or plant where the cores are made and the molds are lined, to the oven and in through the entrance end of the casing, and thence, through the exit end, to points of delivery.

Cars 66, whereon the work, designated W, is loaded, traverse the rails 65 and, in the present instance, are propelled by car pulling means designated 67. According to prevailing practice, the means 67 may consist of pull-cables or endless chains, the latter being schematically illustrated in the drawings. These chains are guided over sprockets or the like 69, housed in pits 70, and are driven by suitable power means (not shown) that may be located in one of the pits. Beyond the ends of the oven, the car pulling means or chains operate in relatively narrow channels in the floor of the plant. These channels merge with the trenches 60 which, by reason of their location, provide especially appropriate accommodations for the car pulling means sub-

stantially throughout the length of the oven. The upper and lower reaches of the endless chains are supported and guided throughout the length of the trenches by upwardly facing channel beams 12. These beams are connected together in properly spaced relation to each other, and are shown as supported from the bottom of the trenches, by upright members 13. Any selected number of plates 15 are adapted to be arranged in variable spaced relation to each other along the top of each trench—in the present embodiment on each side of the car pulling means 67, with their inner edges sustained by the structure composed of the channels 12 and members 13, and their outer edges supported by the floor 6, within rabbeted grooves thereof. The plates 15, by reason of the fact that they may be varied in number and spacing, constitute regulable means for changing the gas recovery capacity of the recirculating ducts or trenches.

Any suitable expedient may be employed for separably connecting the car pulling means 67 to a car. Means for this purpose is more or less schematically illustrated in the drawing as comprising entering and receiving members 76 and 77, one carried by the chain and the other by a car.

In the use of the oven, the work W, illustrated as stacks of large mold flasks, is arranged on the cars so as to be properly spaced from the side walls of the oven and provide free circulation of the hot gas through and about the work. The cars are now moved into the oven by the car pulling means 67 and the doors 12 and 13 closed. With the gas heater 42 in operation, current is turned into the driving motors 45 and 56 of the impeller or blower 41 and the exhaust fan or blower 53, respectively. The hot gas from the heater will be drawn through the conduit 44 to the casing of the impeller 41 and delivered under pressure through the duct 42 and cross ducts 38 to the supply ducts 30, 31 and 32. For a better understanding of a practical application of the invention, it may be related that, in a typical installation, the heater is of six million B. t. u. capacity, and, with the impeller 41 in operation, a static pressure of from 4" to 6" prevails in the oven. In fact, it requires a static pressure substantially within these limits to force the hot gas downward in opposition to the natural tendency of such gas to rise. It is evident from this that the hot gas within the oven is thoroughly diffused and effectively distributed through and about the work and that the efficiency of the oven is accordingly very high. As previously explained, the outlet openings of the supply ducts may be effectively regulated by the damper means associated with such openings in accordance with prevailing practice, and by virtue of the regulable means provided by the plates 15 for altering the recovery capacity of the recirculating ducts or trenches 60, such approximate percentage of the oven atmosphere as may be desired may be reheated and recirculated, the remaining percentage being carried off through the exhaust duct 50 and stack 55. A practical ratio would be about 70% for reheating and recirculation and the remaining percentage for withdrawal, the latter being replaced by atmospheric air entering about the doors and through the heater 42 as combustion air. Some leakage will occur elsewhere, as through the channels wherein the car pulling means is housed exteriorly of the oven and which communicate with the recirculating ducts or trenches 60, as above explained.

At the conclusion of the drying period the doors are opened and the cars are withdrawn from the oven by the car pulling means, in the present instance through the exit end of the oven where the door 13 is located.

In addition to the high efficiency of the oven assured by my novel method of circulation and distribution of the hot gas, the duct arrangement affords maximum space for the accommodation of the work and eliminates all possibility of damage to the ducts from the cause above set forth; and although it is not entirely necessary, it is desirable to continually replace a part of the oven atmosphere with fresh air, as herein provided, in order that the recirculated gas be less contaminated by the vapors given off by the work.

Having thus described my invention, what I claim is:

1. An industrial oven comprising an open end casing including a solid floor, closure means for the open end of the casing supported for movement between open and closed positions, supply duct means situated adjacent the top of the casing for delivering heated gas directly thereto, a trench formation in the floor constituting recirculating duct means disposed below the floor level and opening through said level into the interior of the oven casing, gas heating means and gas impelling means communicatively connected together for the heating of the gas and for the circulation of the same therethrough and having a gas inlet and a gas outlet, conduit means communicatively connecting said gas outlet to said supply duct means, and further conduit means communicatively connecting the recirculating duct means to said gas inlet, whereby to draw gas from the oven casing through the recirculating duct means and move it through the heating means and return it under pressure to the oven casing through said supply duct means, parallel rails supported by the floor, one on each side of said trench formation, and extending out through the open end of the casing to provide a track on which cars may be moved into and out of the oven, and car moving means operating within said trench formation.

2. An industrial oven comprising an open end casing including a top wall, side walls and a solid monolithic floor, closure means for the open end of the casing supported for movement between open and closed positions, a plurality of inter-communicating supply ducts within the oven casing extending substantially the length thereof in close proximity to the top wall, each duct having outlet openings at closely spaced intervals throughout the length thereof for the discharge of gas into the oven, a relatively narrow trench formation in the floor constituting a recirculating duct situated below the floor level and extending substantially the length of the oven casing and opening into the oven through said level, gas heating means and gas impelling means communicatively connected together for the heating of the gas and for the circulation of the same therethrough and having a gas inlet and a gas outlet, conduit means communicatively connecting said gas outlet to the supply ducts, and further conduit means communicatively connecting the recirculating duct with said gas inlet, whereby to withdraw gas from the oven through the recirculating duct and move it through the heating means and return it under pressure to the oven through said supply ducts.

3. An industrial oven comprising the combination and arrangement of parts defined by claim

22 and, in addition thereto, an exhaust duct extending transversely of the oven casing entirely within the plane of the supply ducts and beyond the ends thereof and having openings through which gas is admitted thereto from the oven, and suction means in communication with the exhaust duct.

4. An industrial oven comprising the combination and arrangement of parts defined by claim 1, and, in addition thereto, two series of loose plates adapted to be placed across the top of the recirculating duct in selected number and spaced relation to one another to regulate the gas receiving capacity of the recirculating duct, and means for supporting the two series of plates in laterally spaced relation to each other to afford access therebetween to the car moving means.

5. An industrial oven comprising an open end casing including a top wall, side walls and a solid monolithic floor, closure means for the open end of the casing supported for movement between open and closed positions, supply ducts within the oven casing extending substantially the length thereof in close proximity to the top wall of the casing and having outlet openings for the delivery of gas to the oven, a track consisting of parallel rails supported by and within the floor with their top surfaces in substantially the plane thereof leading into the oven through the open end of the casing, a relatively narrow trench formation in the floor constituting a recirculating duct below the floor level and situated substantially midway between the rails and extending substantially the length of the oven casing and opening into the oven through the floor level, gas heating means and gas impelling means communicatively connected together for the heating of the gas and for the circulation of the same therethrough and having a gas inlet and a gas outlet, conduit means communicatively connecting said gas outlet to the supply ducts, and further conduit means communicatively connecting the recirculating duct with said gas inlet, whereby to withdraw gas from the oven through the recirculating duct and move it through the heating means and return it under pressure to the oven through said supply ducts.

6. An industrial oven comprising the combination and arrangement of parts defined by claim 5, wherein the recirculating duct provides accommodations for means for moving cars into and out of the oven along the said track and wherewith

the cars are adapted to have separable driving connections, car moving means comprising a linear element, a guiding and supporting structure for said car moving means situated in the recirculating duct substantially midway between the sides thereof, a plurality of loose plates, and means for supporting said plates at approximately floor level in spaced relation to each other and between said guiding and supporting structure and the floor adjacent the sides of the recirculating duct, said plates being changeable in number and spacing thereby to constitute regulable means by which the gas receiving capacity of the recirculating duct may be varied.

7. An industrial oven comprising a casing including a top wall, side walls and a floor, the casing being open at both ends, closure means for each end of the casing supported for movement between open and closed positions, three intercommunicating supply ducts within the oven casing extending substantially the length thereof in close proximity to the top wall, two of said ducts being adjacent the side walls of the oven casing and the third being substantially midway between said two, each duct having outlet openings for delivery of gas to the oven, a trench below the floor level and extending substantially the length of the oven and opening into the oven through the floor, gas heating means and gas impelling means communicatively connected together for the heating of the gas and for the circulation of the same therethrough and having a gas inlet and a gas outlet, conduit means communicatively connecting said gas outlet to the supply ducts, and further conduit means communicatively connecting the trench to said gas inlet, whereby to withdraw gas from the oven through the trench and move it through the heating means and return it under pressure to the oven through said supply ducts.
